UNITED STATES PATENT OFFICE.

CHARLES M. RUMBAUGH, OF ELKHART, IOWA.

DOOR-SECURING MEANS.

1,107,362.

Specification of Letters Patent. Patented Aug. 18, 1914.

Original application filed March 24, 1913, Serial No. 756,300. Divided and this application filed March 11, 1914. Serial No. 823,889.

To all whom it may concern:

Be it known that I, CHARLES M. RUMBAUGH, a citizen of the United States, residing at Elkhart, in the county of Polk and State of Iowa, have invented certain new and useful Improvements in Door-Securing Means, of which the following is a specification.

This application is a division of my application Serial No. 756,300, filed in the United States Patent Office, March 24th, 1913.

Among the more important objects of the invention is to provide an improved device of this character, adapted to be connected to a door or closure, to hold the same in an open or closed position, and also to provide a device that will permit the closure to be swung with one thrust to an outward open position and hold the closure in such position.

A further object is to provide a device of this character which will permit the closure when open after releasing the securing means, to be swung to its inward closed position with one thrust and to hold the closure in such closed position, and a still further object is to provide a securing means for the closure in its outward open position and inward closed position which can be released from the inside or outside of the closure.

These and other features, capabilities and advantages of the invention will become apparent from a detailed description of the accompanying drawing in which,

Figure 1 is a perspective view showing an embodiment of the invention connected to a door. Fig. 2 is a sectional view on line 2-2, Fig. 1. Fig. 3 is a top plan view of the improved device showing the door in a closed position in full lines, partly in section, and showing the door open in dotted lines.

Referring to the drawing the numeral 10 designates a bracket preferably of a triangular configuration, the base of which is deflected as at 11 to form feet, which are secured by fastening devices to the frame of the door opening, and adjacent the hinged side of the door. At the apex of the triangular member 10 is formed a bearing 13, through which a journal pin 14 passes. The extremities of this pin pass through lugs 15 which are provided on a casting 15^a and into which casting one end of an arm or bar 16 is preferably screwed. The other end of

this arm 16 is also preferably threaded into a casting 17^a having a bent or enlarged portion 17 within which portion is arranged a slot. Across the door in alinement with the arm 16 is secured a rail or guide way 18 which has notches 19, 20, one near each end of the guide way. This guide way is adapted to pass through the slot of the enlargement 17 of the element 17^a and by means of this slot, the arm may be slid along the guide way 18. The arrangement is such that the enlargement 17 will be at the near end of the guide way 18 when the door is closed, and at the far end of the guide way 18 when the door is open, and consequently when the door is closed, the enlargement 17 will drop into the notch 19 and when the door is open, will drop into the notch 20 and thus lock the door in these respective positions. Obviously the pivot connection of the arm with the bracket 10 is constructed to permit such movement. To release the door when in either of these locked positions, it is only necessary to raise the arm 16 and push the door in the required direction. Thus when the door is in the closed position, by raising the arm 16 and pushing the door outward, the door will swing outward until the enlargement 17 drops into the notch 20 and then lock the door in the outward position, and similarly when it is desired to close the door. To permit releasing the door from the other side thereof, which may be called the inside, a chain 21 is provided, attached to the arm 16 and passing through an opening 22 in the door, preferably adjacent the middle of the guide way 18 and having a ring or handle 23 on the extremity thereof, and which ring or handle serves also as a stop to prevent the chain from dropping through the opening 22.

While there is herein shown and described only one embodiment of the invention, it is to be understood that various changes and modifications may be made by those skilled in the art, within the scope of the claims without departing from the spirit of the invention.

What is claimed as new is:

1. A door fastening device comprising a bracket secured to and projecting from a door casing, an arm pivotally secured at one end to the bracket, a guide way mounted upon a door adapted to swing within the door-way, the opposite end of said arm be-

ing provided with an angular portion having an opening for receiving the said guide way, said arm coöperating with said guide way whereby the arm will be held in a locked position, and means extending through the door for raising the end of the arm with respect to the guide way for releasing the arm.

2. A door fastening comprising a triangular bracket adapted to be secured to the door casing, an arm pivotally secured at one end to the apex of said bracket, a guide way permanently mounted upon one side of a door adapted to swing within the door-way and provided with open recesses intermediate its ends, the opposite end of said arm being slidably mounted upon said guide way and having a portion adapted to enter the recess to lock the arm to the guide way, and means extending through the door and coöperating with the said arm whereby the latter may be released from the opposite side of the door.

3. A device of the character described, embodying a bracket secured to and projecting from the casing of an opening, an arm pivotally connected with the bracket, a guide way mounted upon a closure adapted to swing within the opening and provided with open recesses intermediate its ends, the opposite end of said arm having a sliding connection with the guide way, a portion of said end adapted to enter the recesses by gravity for locking the arm against movement with respect to the guide way at predetermined points in the movement of the arm, and means operable from the other side of the closure for raising the arm out of the recesses for releasing the arm.

4. A device of the character described embodying a bracket secured to and projecting from the casing of an opening, an arm pivotally connected with the bracket, a guide way mounted upon a closure adapted to swing within the opening and provided with open recesses intermediate its ends, the opposite end of said arm having a portion encompassing and having a sliding connection with the guide way, a portion of the arm adapted to enter the recesses for locking the arm against movement with respect to the guide way at predetermined

points in the movement of the arm, and means operable from the other side of the closure for raising the arm to release the same, the said means embodying an actuating device connected with the arm and extending through the closure.

5. A device of the character described embodying a bracket secured to and projecting from the casing of an opening, an arm pivotally connected with the bracket, a guide way mounted upon a closure adapted to swing within the opening and provided with open recesses, the opposite end of said arm having a portion embracing and having a sliding connection with the guide way, a portion of the arm adapted to enter the recesses for locking the arm against movement with respect to the guide way at predetermined points in the movement of the arm, and means operable from the other side of the closure for raising the arm to release it, the said means embodying a flexible member connected with the arm and extending through the closure whereby the arm may be raised from either side of the closure.

6. A device of the character described embodying a bracket secured to and projecting from the casing of an opening, an arm pivotally connected with the bracket, a guide way mounted upon a closure adapted to swing within the opening, the opposite end of said arm having a sliding connection with the guide way, provisions for locking the arm against movement with respect to the guide way at predetermined points in the movement of the arm, and means operable from the other side of the closure for releasing the arm, the said means embodying a flexible member connected with the arm and extending through the closure, and a handle connected with the flexible member, said handle serving as a stop to the passage of the end of the flexible member through the said closure.

In witness whereof, I hereunto subscribe my name to this specification in the presence of two witnesses.

CHARLES M. RUMBAUGH.
